NONGLARE HEADLIGHTING ASSEMBLY

Julius C. Ford, Memphis, Tenn.

Application October 16, 1936, Serial No. 105,847

5 Claims. (Cl. 240—41.35)

This invention relates to an improvement in head lights for automobiles, and consists of an improved construction, arrangement and combination of parts hereinafter described and claimed.

The primary object of my invention is to provide a construction for automobile head lights, in which three sources of lights are provided, one being especially for throwing a concentrated light a long distance ahead of the car, one for directional purposes, and the other one being primarily for use where a more diffused light distribution over a short distance is desired. The construction of the head lights provides means for masking and directing the light from its source in such a manner that at least the major portion if not all of the light is directed along the road surface to be lighted, and substantially all the glare from such lights is prevented from rising above a predetermined level.

A further object of my invention is to provide novel means for adjusting the level in which the rays of light will be projected.

A still further object is to provide a construction in which a housing is employed for the lighting structure and such structure is made as a self-contained-unit, removable from the housing for adjustment, repairs, or other purposes.

The means by which the foregoing and other objects are accomplished, and the manner of their accomplishment, will readily be understood from the following description on reference to the accompanying drawings, in which:—

Figure 1 is a sectional elevation showing the preferred embodiment of my device;

Figure 2 is a front elevation of the device with the lens attached thereto;

Figure 3 is a complete unit for raising and lowering the rear end of the head light assembly;

Figure 4 is a sectional view of Figure 3;

Figure 5 is a sectional view taken along the line 5—5 of Figure 2;

Figure 6 is a complete section taken longitudinally through the forward reflector and rear counter-reflector with the upper portion that connects the two reflectors;

Figure 7 is a view of the counter-reflector at the rear end of the device illustrated in Figure 6;

Figure 8 is a front elevation of Figure 6;

Figure 9 is a longitudinal sectional view of a device similar to that shown in Figure 1, with the exception it can be used either with or without a reflector;

Figure 10 is a front elevation of head lighting device with the lens removed;

Figure 11 is a sectional view of a modified form of the invention;

Figure 12 is a front view of Figure 11 with lens removed;

Figure 13 is a perpendicular view of the conical shaped reflector looking downwardly upon the same.

Referring now to the drawings in which various parts are indicated by numbers and figures, 10 is an elongated housing preferably of circular 10 cross section and having a lens 11 at its forward end secured to the housing by a retaining ring 12 of the usual and well-known type.

Disposed within the housing 10 and accessible on removal of the lens 11 is a unitary structure 15 including a diaphragm 13, having an opening 13A, the major portion of which opening lies below the longitudinal center line of the housing. Behind this diaphragm is a casing 9 having a wall 14 at its rear end, said wall 14 preferably being of general parabolic shape, and being centered on the longitudinal axis of the housing. The cylindrical walls 15 of the casing extend forwardly at a downward incline to the opening 13A in the diaphragm 13, the lower half of the walls 15 being of 25 a circular shape, and the upper portion 15A being flattened and downwardly directed and extending forwardly to said opening 13A at a level preferably very slightly above the longitudinal axis of the casing 10. The lower half of the walls of the 30 casing terminates at the diaphragm 13, and the entire casing is secured to the diaphragm as by brazing, welding, or in any other manner desired.

A reflector 16 is mounted on the inside of the casing 9 and is pitched slightly forward so that 35 its center beam comes slightly below the center or horizontal edge 30 of the inside assembly illustrated in Figure 6. Mounted in reflector 16 is a light bulb 17, to which a suitable current wire 18 leads from a source of current, the light 17 being 40 mounted in the usual socket 19. The upper portion of the diaphragm 13 is countersunk horizontally to form a round and oblong shaped reflector 20 in which is set a socket 21. Into this socket fits a bulb 22 used for directional purposes, and current is supplied by a wire 23 leading to the source of current. The numeral 24 designates a combination concave and oblong shaped reflector at the center of which is formed a socket 25 to receive a bulb 26, current being supplied by a wire 50 27 leading to the source of current. Mounted on the inside of casing 9 is a semicircular counter-reflector 28 connected with the reflector 24 by a plate or bridging wall 29, the two reflectors and the bridging wall being preferably made as a unit 55

cut from a single piece of material. The upper end of the counterreflector and the rear end of the wall 29 intersect to form an edge 30 extending transversely through the casing 9 from one side thereof to the other. When viewed from its front end, the wall 29 is in the form of a lower segment of a circle, as shown at 31. The upper face of this bridging wall is of a dull or non-reflecting color so that light will not be reflected upwardly therefrom. A supporting bolt or cross rod 33 extends transversely through the casing under the rear end of the bridging wall and at the center of its rear edge 40 the counterreflector carries a tongue or tip 42 which engages in a slot 43. The front plate in which the reflector 24 is formed has openings 48 near its margins to receive bolts 49 for securing the same to brackets 49A mounted at sides of the front end of the casing.

Now referring to unit for raising and lowering the rear end of head light assembly, 34 and 34A are nuts through which a bolt 35 passes. This bolt is threaded at one end and has a flanged or shouldered part 36 under which a jam nut 37 screws up snug and tight and holds the bolt 35 firmly in any fixed position. The nut 34 is securely welded or brazed onto a flat piece of steel 38, and the flat piece of steel 38 is securely welded or brazed onto the rear wall of the reflector casing 14, as shown by 39. The nut 34A is likewise securely brazed or welded to housing 10.

The casing 9 of Figure 9 is of the same construction as the casing 9 in Figure 1, but the reflector 16 that is mounted inside the casing in Figure 1 is omitted, and the rear wall 14 serves as a reflector. The parabolically shaped reflector formed by the wall 14 is highly polished between points 56 and 56A on the inside, and this particular portion is pitched slightly forward between these points. The cylindrical walls 15 extend forwardly and downwardly to opening in the diaphragm 13, the lower half of the walls being of circular shape and the upper portion 15A being flattened forwardly and downwardly to the opening 13A in diaphragm. The numeral 61 designates the edge of the circular and oblong shaped depression in the upper portion of the diaphragm, and 65 is the oblong and circular shaped depression on the front end of combinational units of Figures 2 and 10, showing the reflector 24.

The reflector casing 67 shown in Figure 11 is a parabolically shaped member which extends forwardly and downwardly and has cylindrical walls 68 the lower portion of which is of a circular shape where it enters the diaphragm 73 and the upper portion 69 being flattened and inclined forwardly and downwardly. The numeral 70 designates the counterreflector attached to reflector casing 67 at 71. The reflector 16 is pitched at an angle slightly upward.

In using the head lights, directional lights, and dimmer lights, they are wired up to any suitable type of directional control switch and the light 17, light 22, and light 26 are similarly connected to a control switch by means of which either one or all may be turned on at the same time, the details of which switch control having no part of the present invention and which have not been shown. In driving, light 26 may be switched on and used, or it may be switched off, and the large light 17 turned on, showing much further ahead. Should it be so desired, both may be turned on at the same time. It will be particularly noted that so far as the light is con-

cerned, the forward edge of the upper portion 15A of the tubular member 15 prevents any direct rays from rising high enough to blind the driver of an approaching car. The upper portion of reflector 16 is masked and at the same time the lower portion of the reflector 16 is masked by the counterreflector up to center or horizontal edge 30, thereby effectively cutting off those rays which might be reflected from the lower portion of the reflector 16. The rear wall 14, shown in Figures 1 and 9, may be used as a reflector should the reflector 16 be removed. It is preferable, however, to use the reflector such as the reflector 16 in preference to the reflector 14.

In the form shown in detail in Figure 11, the rear end of the casing is formed with a wall 67 which will serve as a reflecting means in the event that the reflector 16 shown in Figure 11 is removed.

I claim:

1. A headlight comprising a housing having an open outer face, a light reflecting means mounted in said housing, said light reflecting means comprising a concave vertically disposed reflecting surface facing toward the open outer face of said housing, a longitudinal conical light discharging means extending forwardly of the vertically disposed reflecting surface and having a top and a bottom portion, the top portion being inclined downwardly toward the outer end and having a reflecting face upon its under surface, the bottom portion being inclined upwardly toward its inner end, a lighting means in the rear end of said conical light discharge means, the inner end of the bottom portion shielding the rays of light from the lower half of the lighting means and the lower half of the vertical reflecting surface, the top and bottom portions of the conical light discharge means being spaced to provide an elongated transversely extending light opening at the outer end of the conical light discharge means, the upper face of the bottom portion constituting a non-reflecting surface, the top and bottom portions being flat at their inner ends and oppositely bowed at their outer ends, the inner end of the bottom portion extending in a straight transverse line at the transverse center of the lighting means and the vertically disposed reflecting surface and in a straight line across the entire width thereof, and a concave reflector facing said vertically disposed reflecting surface and located below the inner end of said bottom portion.

2. A headlight of the class described comprising a housing, a diaphragm at the front of said housing, a lens in front of said diaphragm, said diaphragm having an opening therein elongated horizontally and extending approximately the full diameter of the diaphragm, a casing extending longitudinally in said housing and tapered towards its front end, said casing being secured at its front end against the rear face of said diaphragm about the opening therein, a reflector in the rear end portion of said casing, means for mounting a lamp centrally of said reflector, and a counterreflector extending the full width of the casing in front of said reflector and shielding a full half of the reflector and extending vertically beyond the horizontal diameter of the reflector and terminating in a horizontal edge extending the full width of the casing, said counterreflector serving to prevent projection of glaring light rays from a lamp directly through the casing and the opening in the diaphragm, and the upper wall of the casing being disposed at a

downward incline towards its front end and constituting means for reflecting light rays at a downward incline through the opening in the diaphragm.

5. 3. A headlight comprising a housing, a diaphragm at the front of said housing, a lens in front of said diaphragm, said diaphragm having its lower portion formed with an opening having a horizontally extending longitudinally arcuate upper edge, a casing extending longitudinally in said housing with its front end secured to the diaphragm about the opening thereof, a reflector in the rear portion of said casing having a bulb receiving socket at its center, the upper wall of 10 the casing being transversely arcuate and extending at a downward incline towards its front end for directing light rays through the opening in the diaphragm at a downward incline, a counterreflector in the casing in front of the reflector, said counterreflector consisting of a segment of a sphere having its concaved side facing said reflector and constituting a shield covering a portion of the reflector and terminating in a horizontal edge extending the full width of the 15 casing, a plate extending forwardly from the marginal edge of the counterreflector to the front end of said casing for the full width of the casing, said plate being arcuate transversely and disposed at a forward downward incline, and 20 an auxiliary reflector below the front end of said plate provided with a bulb receiving socket.

4. A headlight of the class described comprising a lighting unit assembly, said lighting unit assembly comprising an elongated casing having 25 a transversely arcuate upper wall extending at a downward incline towards its front end, the rear end of said upper wall terminating in a vertical reflector constituting a continuation of the upper wall, a lower wall having a non-reflecting upper surface arranged in spaced relation below the upper wall, the upper and lower walls being spaced at their outer ends to provide a light emitting opening, the lower wall extending on an 30

incline upwardly from the outer end toward the inner end, a light bulb carried centrally of the vertical reflector, the upper wall having a reflecting surface upon the under side for directing light rays downwardly, the inner end of the 5 lower wall extending transversely of the casing for the full width of said casing and being spaced upwardly to a point slightly above the focal point of the reflector and slightly below the horizontal plane of the longitudinal central axis of the light 10 bulb, and in front of the light bulb to prevent the projection of glaring light rays from said bulb outwardly from said casing in an upward direction, and a counterreflector extending upwardly from said casing to the inner end of the lower 15 wall and facing the bulb and the vertical reflector.

5. A headlight comprising a housing, a diaphragm at the front of said housing, a lens in front of said diaphragm, said diaphragm having 20 its lower portion formed with an opening having a horizontally extending longitudinally arcuate upper edge, a casing extending longitudinally in said housing with its front end secured to the diaphragm about the opening thereof, a reflector 25 in the rear portion of said casing having a bulb receiving socket at its center, the upper wall of the casing being transversely arcuate and extending at a downward incline towards its front end for its full length for directing light rays 20 through the opening in the diaphragm at a downward incline, a counterreflector in the casing extending the full width thereof in front of the reflector, said counterreflector consisting of a segment of a sphere having its concaved side 35 facing said reflector and constituting a shield covering a portion of the reflector and terminating in a straight horizontal edge extending the full width of the casing, and a wall extending forwardly from the upper portion of the counter- 40 reflector to the diaphragm.

JULIUS C. FORD.
